L. K. SNELL.

MOTOR VEHICLE.

APPLICATION FILED DEC. 1, 1916.

1,321,157.

Patented Nov. 11, 1919.

UNITED STATES PATENT OFFICE.

LYLE K. SNELL, OF DETROIT, MICHIGAN, ASSIGNOR TO CADILLAC MOTOR CAR COMPANY,
OF DETROIT, MICHIGAN, A CORPORATION OF MICHIGAN.

MOTOR-VEHICLE.

1,321,157.

Specification of Letters Patent. Patented Nov. 11, 1919.

Application filed December 1, 1916. Serial No. 134,514.

To all whom it may concern:

Be it known that I, LYLE K. SNELL, a citizen of the United States, and resident of Detroit, Wayne county, State of Michigan, have invented certain new and useful Improvements in Motor-Vehicles, of which the following is a specification.

This invention relates to motor vehicles, and particularly to built-up metallic panel constructions especially adapted for use as vehicle running boards.

One of the objects of this invention is to provide a metallic panel having maximum strength with a minimum of weight.

Another object is to provide a metallic panel which is simple in construction, comparatively inexpensive to manufacture and permits of an easy assembly of its various parts.

These and other objects will appear from the following description taken in connection with the accompanying drawings, which form a part of this specification, and in which:

Figure 1 is a fragmentary side elevation of a motor vehicle frame with my improved running board mounted thereon;

Fig. 2 is a plan view with portions broken away of the assembly illustrated in Fig. 1;

Fig. 3 is an enlarged transverse sectional view substantially on the line 3—3 of Fig. 2; and

Fig. 4 is an enlarged longitudinal, fragmentary sectional view, substantially on the line 4—4 of Fig. 2.

Referring to the drawings, 10 illustrates a chassis frame side member, to which hangars or supporting irons 11, may be suitably secured as by rivets 12. A running board 13, the construction of which will be presently described in detail, may be arranged on the members 11, with fenders 14, and a splasher 15, suitably secured to the ends and a side, respectively.

The running board 13, which is of a built up metallic construction, comprises a relatively rigid, unbendable plate 16, as of hard cold rolled steel. On account of the thinness of the plate 16, longitudinal extending

stiffening members 17, of angular shape or channel section, are arranged longitudinally of the plate 16, and secured to the lower portion thereof such as by welding or brazing at 18. The stiffening members may be

of a malleable metal, such as a forming or 55 hot rolled soft steel.

End and side members 19, of channel cross section, also formed of a malleable metal such as soft steel, are adapted to extend around the entire perimeter of the 60 panel 16, and to have their upper flanged portions 20 suitably spot welded, or otherwise secured, at 21, to the under portion of the plate 16. The end and side members 19, it will be noted, form an inner frame for the 65 running board 13. An outer one-piece frame being partially mitered, as at 22, is adapted to surround the inner frame members 19, and to be secured in position by striking up 70 its lower portion, as at 23, and crimping 24, after the insertion of a matting or cover 25, preferably of cork or similar material.

A plurality of connecting pieces or brackets 26, are adapted to have their flanges 26', 75 which are formed on forked arms 27, suitably secured as by rivets 28, to the under-side of the plate 16.

The board 13, after being constructed as a unit, as above described, is adapted to be 80 mounted on the supporting irons 11, by arranging the flanged portions 29, of the stiffening members 17, which also form spacers, on the web portion 30, of the supporting irons. It will be noted that the supporting 85 irons are provided with slots, 31, through which may be inserted bolts 32, and threaded to the bosses 33, of the brackets 26. Of course, a suitable gasket 34, may be arranged between the end of the bolt and the 90 web 30, of the supporting irons 11. The rear end of the front fender and the forward end of the rear fender 14, may be suitably secured to the side of the running board 13, as by bolts 35, and spacing collar 36.

While I have described and will specifically claim what I deem to be a preferred embodiment of my invention, it will be obvious to those skilled in the art that various 100 modifications and changes may be made without departing from the spirit and scope hereof.

Having thus described my invention, what I claim and desire to secure by Letters Patent 105 is:

1. In a device of the class described, the combination with a metallic plate, a plural-

- ity of angle irons extending longitudinally of said plate and having one of their respective flanges suitably secured thereto, bracket members suitably secured to the under side of said plate, a supporting member, means for detachably connecting said bracket to said supporting member, said angle irons serving to stiffen said plate and to space it from said supporting iron.

10 2. In a device of the class described, the combination with a metallic plate, a plurality of angle irons extending longitudinally of said plate and having one of their respective flanges suitably secured thereto, bracket members suitably secured to the under side of said plate, a supporting member, means for detachably connecting said bracket to said supporting member, said angle irons serving to stiffen said plate and to space it from said supporting member, end and side members of channel cross-section having one of their respective flanged portions welded to said plate.

15 3. In combination, an inflexible flat metallic plate, a frame adapted to surround the edges of said plate, comprising a malleable member of channel cross-section having a flanged portion welded to said plate, a plurality of malleable stiffening members of channel cross-section welded to the under side of said plate, connecting members suitably secured to the under side of said plate, a supporting member, and means for detachably securing said supporting member to said connecting members.

20 4. In combination, a rectangular flat metallic plate, a malleable metal frame of channel cross-section extending around the perimeter of said plate and suitably welded thereto, a relatively soft cover plate adapted to rest on said first plate, an outer frame member of forming metal having channel cross-section, said outer frame member adapted to inclose said first mentioned frame member, its upper flange being adapted to extend inwardly over said cover plate, the upper and lower flanges of said outer frame being crimped to maintain same in position.

25 5. In combination, a rectangular flat metallic plate, a malleable metal frame of channel cross-section extending around the perimeter of said plate and suitably welded thereto, a relatively soft cover plate adapted to rest on said first plate, an outer frame member of forming metal having channel cross-section, said outer frame member adapted to inclose said first mentioned frame member, its upper flange being adapted to extend inwardly over said cover plate, the upper and lower flanges of said outer frame being crimped to maintain same in position, a plurality of malleable metal stiffening members of channel cross-section extending longitudinally of said plate and welded to the under side thereof, a supporting mem-

ber extending transversely of said stiffening members, and means for detachably securing said plate to said supporting member.

6. In combination, a rectangular flat metallic plate, a malleable metal frame of channel cross-section extending around the perimeter of said plate and suitably welded thereto, a relatively soft cover plate adapted to rest on said first plate, an outer frame member of forming metal having channel cross-section, said outer frame member adapted to inclose said first-mentioned frame member, its upper flange being adapted to extend inwardly over said cover plate, the upper and lower flanges of said outer frame being crimped to maintain same in position, a plurality of channel irons extending longitudinally of said plate, said irons being welded to the under side of said plate, and a plurality of supporting members extending transversely to said irons, said stiffening members being adapted to rest on said transverse members, and threaded means for connecting said plate with said supporting members.

7. In combination, a rectangular flat metallic plate, a malleable metal frame of channel cross-section extending around the perimeter of said plate and suitably welded thereto, a relatively soft cover plate adapted to rest on said first plate, an outer frame member of forming metal having channel cross-section, said outer frame member adapted to inclose said first-mentioned frame member, its upper flange being adapted to extend inwardly over said cover plate, the upper and lower flanges of said outer frame being crimped to maintain same in position, a plurality of channel irons extending longitudinally of said plate, said irons being welded to the under side of said plate, a plurality of supporting members extending transversely to said irons, said stiffening members being adapted to rest on said transverse members, and threaded means for connecting said plate with said supporting members.

8. In combination, a rectangular flat metallic plate, a malleable metal frame of channel cross-section extending around the perimeter of said plate and suitably welded thereto, a relatively soft cover plate adapted to rest on said first plate, an outer frame member of forming metal having channel cross-section, said outer frame member adapted to inclose said first-mentioned frame member, its upper flange being adapted to extend inwardly over said cover plate, the upper and lower flanges of said outer frame being crimped to maintain same in position, a plurality of channel irons extending longitudinally of said plate, said irons being welded to the under side of said plate, a plurality of supporting members extending transversely to said irons, said stiffening members being adapted to rest on said transverse members, and threaded means for connecting said plate with said supporting members.

transversely to said irons, said stiffening members being adapted to rest on said transverse members, a plurality of bifurcated connected members riveted to the under side 5 of said plate, and means for detachably securing said connecting members with said supporting members.

9. In a motor vehicle, the combination with a side frame member, of a running board supported from said frame member 10 and extending along the side of the vehicle; and front and rear fenders, the inner ends of which are secured to the ends of said running board and spaced slightly apart 15 therefrom, said inner ends also being arranged in line with and forming continuations of the said running board.

10. In a motor vehicle, the combination with the frame and body supported thereon, 20 of a running board of reinforced sheet metal secured to the frame and having flanged ends, front and rear fenders suitably sup-

ported and having the ends next said running board suitably flanged, bolts securing the adjacent flanges of said fenders and said 25 running board together, and spacing collars on said bolts between said flanges.

11. In a motor vehicle, the combination with a side frame member, of a plurality of supporting brackets carried by and extending outwardly from said frame member at 30 intervals along the same, and which brackets are U-shaped in cross section and are provided each with a plurality of longitudinally extending slots; a running board supported 35 upon said brackets and extending parallel with said frame; and bolts extending through said running board and through said slots, and arranged between the sides of said U-shaped brackets, for securing said 40 running board to said brackets.

In testimony whereof I affix my signature.

LYLE K. SNELL.
